UNITED STATES PATENT OFFICE.

LOUIS ELYEMAE KELLER, OF OIL CITY, PENNSYLVANIA.

BRAKE-BEAM.

No. 858,457.

Specification of Letters Patent.

Patented July 2, 1907.

Application filed February 12, 1907. Serial No. 356,995.

To all whom it may concern:

Be it known that I, LOUIS ELYEMAE KELLER, a citizen of the United States, residing at Oil City, in the county of Venango and State of Pennsylvania, have invented certain new and useful Improvements in Brake-Beams, of which the following is a specification, reference being had therein to the accompanying drawing.

This invention is an improvement in railway brake mechanisms, and relates particularly to a brake beam.

10 The object of the invention is the improvement of the construction of a single-piece brake beam, which is very simple and durable in structure.

Another object of the invention is the improvement of the construction of the shoe-frames and yoke-supporting head, co-operating with a brake beam constructed in accordance with the present invention.

With these and other objects in view, the invention consists of certain novel constructions, combinations, and arrangements of parts, as will be hereinafter fully 20 described and claimed.

In the drawings: Figure 1 is a perspective view of a brake beam constructed in accordance with the present invention, and showing a yoke and its supporting-head assembled with the brake beam. Fig. 2 is an inverted 25 plan view of my brake beam, and showing a pair of shoe-frames and a yoke-supporting head positioned thereon. Fig. 3 is a transverse, sectional view of the brake beam taken on line 3, 3, Fig. 2, and looking in the direction of the arrow. Fig. 4 is a transverse sectional 30 view of the brake beam taken on line 4, 4, Fig. 1, and looking in the direction of the arrow. Fig. 5 is a fragmentary, vertical sectional view of the yoke and its supporting head. Fig. 6 is a fragmentary, vertical sectional view of another embodiment of the yoke and 35 supporting head.

Referring to the drawings, 1 designates a hollow, single-piece brake beam, triangular in cross-section, which comprises a base portion 2, inclined walls 3, 3, and a single reinforcing rib 4. The inclined walls 3 40 converge toward their upper edges and terminate in the integral, longitudinally-extending reinforcing rib 4, which rib 4 is preferably of substantially the same thickness as the combined thickness of the two walls 3, thereby greatly increasing the strength of the entire brake beam 1, making it practically impossible to bend or break the beam, as the walls 3 are greatly reinforced and strengthened at their integral edges, while the lower edges are integrally connected and braced by the base-portion 2. It will, therefore, be 45 seen that the walls are provided with vertical, reinforcing means, to wit: the comparatively broad, single rib 4, and horizontal reinforcing means, to wit: the broad horizontal base portion 2. By reason of the vertical, reinforcing means 4 and the horizontal reinforcing means 2, my single-piece, hollow brake beam is practically non-destructible, and consequently, of great

strength, so as to provide for any vertical or horizontal strain thereon.

My hollow, single-piece brake beam is of the same dimensions throughout its entire length, thereby facilitating the adjustment and assembling of the shoe-frames and the yoke-head thereon, as will be herein-after pointed out. It is very desirable that the reinforcing rib 4 be of the thickness above mentioned, because, it not only greatly reinforces the entire structure, 60 but it would be practically impossible to have the rib of the same thickness as one of the walls, and, therefore, when constructing the brake beam, it is easy to form a comparatively thick reinforcing rib at the adjoining, integral edges of the walls or sides 3. 70

Each shoe-frame 5 is provided with a brake beam receiving-head 6, Fig. 3, which head 6 comprises a base portion 7 inclined walls 8, 8, terminating at their upper ends in vertical parallel walls 9, 9, which walls 9 are integrally connected by a horizontal top-portion 10. 75 The inclined walls 8, 8 engage the outer face of the walls 3 of the brake beam, while the vertical parallel walls 9 of the head 6 engage the vertical sides of the reinforcing rib 4. The shoe-frames 5 can be quickly adjusted longitudinally upon the brake beam 1, and fixedly secured in an adjusted position, upon said brake beam, by any suitable fastening means, as for instance, bolts or rivets 11, which bolts or rivets 11 are passed through registering apertures formed in the single reinforcing rib 4 and the vertical, parallel walls 9 of the head 6 of 80 the shoe-frames. 85

The yoke-supporting head 12 comprises a horizontal base 7', inclined walls or sides 8', terminating at their upper ends in vertical, parallel walls 9', 9', which upper walls 9' are integrally connected by a horizontal top-portion 10'. It will be noted that the head 12 is similarly constructed to the heads 6, and is secured to the brake beam, preferably, in the same manner. The head 12 can be quickly slid or adjusted longitudinally upon the brake beam, and secured in its adjusted position, owing to the brake beam being of the same construction throughout its entire length. A depending ring 13 is integral with the base portion 7' of the yoke-supporting collar 12. Referring particularly to Fig. 5, the base 7' and the ring 13 are provided with a vertical 100 aperture 14, which converges from its upper end to its lower end. A stem 15 is positioned within aperture 14, and said stem is of varying dimensions throughout its entire length, because it converges from its outer or upper end toward its inner or lower end, so as to fit snugly 105 in aperture 14, to permit a free, rotary movement thereof. Yoke 16 is provided at its upper end with an aperture 17, within which is positioned the lower end of stem 15. Suitable fastening means, as for instance, a pin or bolt, extends through the upper end of the yoke 16 and the lower end of stem 15. It will be obvious 110 that registering apertures are formed in the sides of the

yoke 16, and in the stem 15, within which said pin or bolt 18 is positioned. It will, therefore, be seen that the yoke 16 can be freely rotated, so that a lever can be placed therein, irrespective of whether the lever is actuated from the right or left side of the mechanism or car carrying said mechanism.

The embodiment depicted in Fig. 6 is of substantially the same structure as that depicted in Fig. 5, except that in this embodiment, the stem 15' is integral with 10 the upper end of the yoke 16'. The stem 15 converges from its upper end to its lower end, and is positioned within aperture 14 of the head 12.

My single-piece beam is of a very simple structure, and comparatively inexpensive to construct, and has 15 many advantages over a sectional brake beam. Furthermore, a single-piece, triangular-shaped brake beam is superior to a sectional triangular brake beam in many instances, among which may be mentioned the fact that in a single-piece brake beam, the fastening means for 20 securing the sections together are obviated. Furthermore, a single rib, constructed in accordance with my invention performs the same function as a plurality of ribs in a sectional brake-beam, besides performing the function of the connecting and fastening means for the 25 contiguous upper edges of the walls 3.

It will be noted that the yoke-supporting head, in Fig. 1, is not positioned in its proper central position upon the brake beam 1, as I have shown it off-center on the brake beam, for the purpose of not only illustrating 30 the fact that, for convenience, it may be at any time, positioned at any point upon the brake beam, owing to the fact that the brake beam is of the same dimensions throughout its entire length, but also for the purpose of showing the central aperture of the reinforcing rib 4.

35 The yoke and head, shown in Fig. 6, are assembled in the following manner: The stem 15' of the yoke is heated prior to inserting the same in the aperture 14, and as the stem 15' is formed of greater length than the aperture 14', the upper or outer end thereof projects 40 between the sides 8' of the yoke, so that the extended end, while in its heated condition, can be hammered down, causing the heated stem to fill the aperture 14, thereby producing the tapering structure.

While I have described my beam as being particularly adapted to be used in connection with a 45 brake mechanism, and have specified the beam in the claims as a "brake beam," it is to be understood that, owing to the peculiar structure of my beam, it is susceptible to being used in structural 50 work for buildings or as vehicle axles, or for any purpose in which a beam of my type may be used.

What I claim is:

1. In a brake mechanism, the combination of a triangular-shaped brake beam provided with a reinforcing rib, and 55 shoe-frames provided with heads positioned upon said brake beam, the head of each shoe-frame comprising a horizontal base, inclined walls integral with said base and converging toward their upper ends, said inclined walls

terminating at their upper end in integral, vertical, parallel walls, and a horizontal top-portion connecting and integral with the upper ends of the vertical walls. 60

2. In a brake mechanism, the combination of a triangular-shaped brake beam provided with a single-reinforcing rib, a yoke-supporting head positioned upon said brake-beam, a yoke carried by said head, said yoke-supporting 65 head comprising a horizontal base, inclined walls integral with said base and converging toward their upper end and terminating in integral, vertical, parallel walls, and a horizontal top-portion connecting and integral with the upper end of said vertical walls. 70

3. In a brake mechanism, the combination with a brake beam, of a yoke-supporting head carried by said brake beam, said head provided with a base, a depending ring integral with said base, said base and ring provided with an aperture converging from its upper end to its lower 75 end, a stem positioned within said aperture, said stem converging from its upper end toward its lower end, and a yoke carried by said stem.

4. In a brake mechanism, the combination with a brake beam, of a yoke-supporting head carried by said brake beam, said head provided with a base, said base provided with an aperture tapering from its upper end to its lower end, a stem tapering from one end to its opposite end, positioned within said aperture, a yoke, said stem extending through the upper end of said yoke, and transverse fastening means extending through the upper end of said yoke and the lower end of said stem and securing said yoke and stem together. 80

5. As a new article of manufacture, a hollow, single-piece brake beam of the same dimensions throughout its 90 entire length and comprising a base, inclined walls integral with said base and terminating at their upper edges in a single, integral reinforcing rib.

6. A hollow, single-piece brake beam, comprising a base, inclined walls integral with said base and converging toward their upper edges, and a reinforcing rib integral with the upper edges of said walls and of greater thickness than each wall. 95

7. As a new article of manufacture, a hollow, single-piece brake beam, triangular-shaped in cross-section, and provided with a single, reinforcing rib integral with a plurality of its walls. 100

8. As a new article of manufacture, a single-piece brake beam, triangular-shaped in cross-section, and provided with a reinforcing rib integral with a plurality of its 105 walls.

9. A hollow, single-piece brake beam, comprising inclined walls connected at their lower ends by an integral, horizontal base, constituting horizontal, reinforcing means for said walls, and said walls integral at their ends and terminating in a single, vertical rib, constituting vertical, reinforcing means for said walls. 110

10. A hollow single-piece brake beam of the same dimensions throughout its entire length, triangular-shaped in cross-section, and provided with a longitudinally-extending, reinforcing rib integral with and at the adjoining edges of a plurality of its walls. 115

11. A hollow, single-piece brake beam of the same dimension throughout its entire length, said beam triangular-shaped in cross-section, and a plurality of its walls provided with a single, integral, vertical reinforcing means. 120

In testimony whereof I hereunto affix my signature in presence of two witnesses.

LOUIS ELYEMAE KELLER.
